INSERTABLE CIRCULATION STARTER FOR
WELL STRINGS

Jesse E. Hall, Los Angeles, Calif.

Application August 24, 1936, Serial No. 97,554

13 Claims. (Cl. 255—27)

This invention is a means adapted to be inserted at any desired point in a "string" of conduits, of one or another of the several kinds commonly employed in the deep well industry, and has the principal function of generating pressures of much higher degree than is practical with the usual circulating and other pumps used for the purpose of flowing drilling or other liquids in the given string of tubular parts then in the well or drilled hole, the purpose of the high pressure produced by the instant invention being to establish liquid circulation which, for one or another of reasons well known to those skilled in the art, may have been lost and is not practically re-establishable by the divers circulating equipment now in general use in the deep well industry.

Thus, an object of the invention is to provide means whereby to readily establish circulation which may have been choked in or about a long string of casing in a well hole.

Another object is to provide for the opening of circulation between a drill pipe and a surrounding casing or the natural formation through which the tool is drilling so that the circulating fluid may be restored to balance and circulated to the top; that is to break the choking effect of thick settled mud tending to accumulate at the bottom of the hole during cessation of normal pumping for incidental reasons.

Further an object is to provide a method and means for the making of a safe, speedy and practical "squeeze out" job in cases where an attempted cement shut-off has resulted in a leak back into the casing being set; safe because of the fact that the high pressure necessary to the squeeze out operation is set up immediately at the cemented end of the casing and its upper part protected from injury by this high pressure.

An object is to provide a high pressure generator which can be readily, practically and safely directly incorporated in a well string of tubular parts either in a position at the head works of the well or hole, or at a position desired in the lower portion of the string parts in the well hole; that is, this fluid pressure generator is a unit insertable as an element in the drilling, the casing or the tubing string, as the use may require.

Still another object is to provide pressure generating, circulation starter which is of simple and substantial structure, is of low cost, and may be readily installed as a unit, or stored or transported as such.

And an object is to provide for the operation of this starter by its operative connection with

the usual kelly bar, pump swivel connection and elevator works as a working combination.

The invention consists of certain advancements in this art as set forth in the ensuing disclosure and having, with the above, additional objects and advantages as hereinafter developed, and whose construction, combination and details of means, and the manner of operation, and the novel method, will be made manifest in the description of the herewith illustrative embodiment; it being understood that modifications, variations and adaptations may be resorted to within the scope, principle and spirit of the invention as it is more directly claimed hereinbelow.

Figure 1 is an axial section of the pressure-generating, starter unit; partly broken away. Figure 2 is an elevation of by-pass control means of the unit. Figure 3 is an elevation of a valve push rod. Figure 4 is an axial section of a nipple connection for rotational coaction of the starter unit and string parts suspended thereby. Figure 5 is an elevational view of the elevator and starter unit combination.

Figure 6 is a diagram of the apparatus in situ for making a squeeze out, cement shut-off.

In its disclosed embodiment the fluid pressure generating unit includes a foot coupling 2 of suitable type to the lower side of which there may be connected that portion of any conduit string S through which it is desired to establish a requisite or high degree of pressure to accomplish the opening or maintaining of liquid circulation, or such other function as the particular job may entail, such, for instance as the breaking of circulation about a fish, in a fishing job, and through the string of pipe of the fishing tool employed.

Securely attached to the upper end of the coupling 2 is a tubular pillar 3 which forms a standing support for a valve system later described. Fixed on the upper end of the pillar 3 is a suitable valve cage 4 having an expansion spring 5 normally thrusting an imposed ball valve 6 upward to its ring seat 7 fixed in the cage 4 by the lower end of an upper valve cage 8 screwing into the cage 4.

The lower portion of the valve cage 8 has lateral ports 9 to its exterior and has a set of guide fingers 10 supporting an axially movable push rod 11 whose lower end freely rests on the lower ball valve 6. The upper end of the valve cage 8 is somewhat enlarged at 8a and has an internal, expansion spring 12 normally thrusting upward a ball valve 13, which is here shown as of considerably larger size than the lower valve 6. The

valve 13 seats upward against a ring seat 14 fixed in the upper end of the cage 8 by the lower end of a standing head or core, of cylindrical form, 15, of about the same diameter as the enlarged 5 part 8^a of the upper cage 8; the core 15 screwing into the latter cage at 16.

In the normal function of this apparatus the assembly of parts just above described, from the coupling 2 to the head or core 15, constitutes 10 a standing organization in combination with the attached string S extending therebelow, or other subjoined tool or devices as the job may require.

The upper face of the core 15 is recessed or notched at 17 for cooperation with an adjacent, 15 opposed device forming a part of the working assembly of the unit as will now be set forth. This working assembly includes an upper tool joint 20 of any suitable type or other preferred form of connector for attachment to an upper 20 works such as a kelly bar K to the upper end of which is connected the usual hog pump line L and its swivel joint J, this being hung by bail B to the elevator hook H, thus providing for vertical reciprocation of the kelly and subjoined apparatus while the hose line communicates with a 25 suitable source of liquid supply, which may be a pump, or a sand pit, or other source.

The lower end of the tool joint 20 is screwed into the upper end of an elongated working barrel 30 21 in which there is also screwed the crown 22 of a tubular ram 23 which slidably fits in the bore of the hollow core 15 and whose lower end 24 closely approaches the closed valve 13 when the ram is in its lower position, as shown in Fig. 1, 35 at the end of a down or suction stroke of the working barrel 21.

The ram 23 is provided for the purpose of occasionally forcibly opening the lower valve 6 against high pressure therebelow to by-pass the 40 liquid upward around the valve 13 while this is held open by the ram tube 23, and still provide for the normal working stroke of the barrel without opening the by-passing valves at the same instant. With this in view the crown 22 of the 45 ram 23 has its lower face provided with strike blocks or teeth 24 complementary to the opposed notched face 17 of the upper end of the core 15.

In normal stroke of the working barrel as to the standing core 15 the strike blocks 24 will approach or perhaps contact the rim of the core 50 without the toe of the ram 23 engaging the valve 13, but if it is desired to ram the valves 6-13 open to by-pass the pressure it is necessary to turn the barrel 21 and bring the blocks 24 into register 55 with the notches 17 of the core and thus permit added down stroke of the barrel and the ram 23 to repress the valve 13 to engage the rod 11 and by this press the valve 6 from its seat 7.

The barrel 21 has a working fit on the core 15 60 and on the enlarged part 8^a of the cage of the upper valve 13 and there is so formed an annular space 25 to which the lateral ports 9 lead from the cage 8; this space continuing down to and being closed by the upper end of a cylindrical, working shoe 26 the upper end of which screws at 65 27 into the foot of the barrel 21. The shoe 26 has a working fit on the elongated pillar 3 of the standing assembly. Fluid seal of the relative sliding surfaces of the unit may be had by a polished fit of the parts or by packing, as desired, or both.

In order to provide for the rotation of the parts of apparatus subjoined to the foot coupling 2 in cases where it is deemed required an elongated 70 nipple 28 is screwed onto the coupling 2 and

freely slidably receives the working shoe 26; the lower end of the nipple having vent ports 29 for surging liquid as the shoe reciprocates in the nipple. Relief ports 30 are provided for a like purpose in the head of the barrel at about the location of the head notches 17.

The nipple 28, Fig. 4, is keyed for reciprocation on the shoe 26 as by a key 31 in the latter engaging in a keyway 32 in the bore surface of the nipple so that rotation of the working barrel 21 by 10 means of the kelly K or otherwise will also rotate the string S and the standing assembly pillar 3 and its attached valve set.

The lower portion of the keyway 32 has a lateral offset 33 into which the key 31 of the shoe 26 may 15 be turned when it is desired to turn the strike blocks 24 into register with and for movement into the notches 17 to ram the valves 6-13 open for bypass from below the lower valve 6.

The space 25 below the standing valve cage 4 in 20 the barrel 21 constitutes an enlarging suction chamber as the working shoe 26 slides down on the standing pillar 3 and since the valve 6 is pressed up to its seat by the spring 5 it will be seen that the vacuum established in the chamber 25 causes the upper valve to be drawn from its seat 14 if, indeed, it is not forced therefrom by pump pressure on fluid in the hose line L. On the return or up stroke of the working barrel 21 and its shoe 26 the liquid trapped in the chamber 25 below the now closed valve 13 will be subjected to a degree of pressure higher than that obtaining in the ducts in the parts below the lower valve 6 and this will be forced open; the necessary pressure being generated by the upward pull of the kelly K attached to the unit coupling or joint 20.

From the above it will be seen that any desired degree of pressure may be built up in the string S below the smaller valve 6 until free circulation 40 is re-established in the well if it is practically possible without destruction of the particular apparatus employed.

Fig. 6 illustrates a method for making a "squeeze out" cement shut-off in an instance where 45 the first cement plug C proves to be a failure and allows a formation leak back into the cemented casing A. By the instant invention a suitable casing packer P is lowered to the bottom of the casing C by the unit foot coupling 2 and its associated unit assembly above set forth so that this pressure generating unit is located immediately at the cemented bottom of the casing A. The packer P is set in the casing and green cement is pumped down the string to the unit and 50 discharged below the packer. The fluid pressure in the unit is now built up to a very high degree or until it is shown that the green cement is being squeezed out into the crevices in the first plug and to the formation and the leaks thus 55 choked off. At no time will the casing above the packer be subjected to the high, squeeze out pressure set up below the packer; the casing being therefore preserved.

If it be desired to effect an upward jarring 60 reaction between elements of a string of tool parts with which the present circulation starter is employed it is only necessary to run the working shoe upward until its upper end face 26^a abuts the lower end surface of the lower 65 valve cage 4. And this engagement of the standing parts and the upper working assembly is also made when it is desired to pull the whole apparatus and attached structure from a hole 70 or well.

It is possible to invert the unit and attach a packer to its lower end and then operate the then upper valve assembly and pillar to take a sample of formation from below the set packer 5 by pulling the unit while the valves are closed with the entrapped sample.

It will be seen that in cases where fluid under pressure is supplied to the chamber 25 it exerts an available down pressure or force on the 10 end 26^a of the shoe since this is of larger area than the opposed area of the inner end of the ram tube 23; this excess pressure aiding in the downward movement of the barrel assembly and the inductive elongation of the suction chamber.

15. What is claimed is:

1. A deep well circulation starter including a standing assembly having means for attachment of a subjacent instrument and including upwardly spring-closed valves, a cage device in 20 which the valves are operative and having a lateral outlet therebetween and a hollow pillar on which said device is fixed, and a working assembly including a barrel sliding on said device and having a shoe sliding on the pillar and forming below said device a suction and discharge chamber communicating with said outlet; one of said valves operative on down stroke of the barrel 25 to admit fluid to the chamber and to close on the up stroke of the barrel, and the other valve operative on the up stroke of the barrel to pass fluid displaced from the chamber to the hollow pillar to establish circulation; the upper valve being of greater flow capacity than the lower.

25. 2. A starter as set forth in claim 1, and including means for concurrently opening the valves to by-pass fluid pressure from below the lower valve.

3. A fluid circulation starter including a lower standing assembly having means for attachment of a subjacent instrument in which pressure is to be established, and an upper working assembly forming with the lower assembly a suction and displacement chamber, a set of vertically spaced, yieldingly closed differential valves included in the standing assembly, and means providing for communication from the space between the valves to and from said chamber; one of said valves forming an intake and opening on down stroke of the working assembly to admit fluid therefrom to said chamber, and the other valve forming an exhaust larger than the intake and operating on the up stroke of the working assembly to pass fluid to the standing assembly and parts therebelow; the working assembly being connective to a source of supply.

4. A starter as set forth in claim 3, and including means operative by the working assembly for opening both valves at once to effect a fluid by-pass from the high pressure side.

5. In apparatus of the class described; a hollow pillar through which pressure fluid is to be circulated, a valve cage device on said pillar having lateral flow ports, a spring closed valve in said cage below said ports to close flow up from said pillar, and an upper valve to admit fluid to the cage and being spring closed to stop upward flow, and a working barrel slidably fitting said cage device and said pillar and forming therebetween a suction and displacement chamber with which said ports communicate; said barrel having means for attachment to a source of fluid said pillar having a hollow core fixed above the upper valve and forming a fluid chamber of less

volume than the said displacement chamber; whereby as the barrel is moved downward fluid is drawn into the displacement chamber without setting up a detrimental back pressure in the said means when connected to a source of supply.

6. Apparatus as set forth in claim 5, and in which said means consists of a reciprocative elevator apparatus whereby the working barrel may be actuated to establish circulation pressure on the up stroke of the barrel and including a 10 guide sleeve working in the bore of said core.

7. A circulation starter for a deep well string including relatively reciprocative barrel and valve assemblies which cooperate to form a suction and displacement chamber; said assemblies 15 constituting a unit one end of which is reciprocatively connected to an actuator and source of fluid supply and the other end to a part in which circulation is to be established by discharge of fluid from said chamber on the up stroke of the 20 working barrel assembly and an inflow chamber of smaller capacity than, and for liquid supply to, the displacement chamber without detrimental back pressure in the said connective assembly.

25. 8. A circulation starter including a working barrel assembly attachable to a fluid supplying actuator, a standing valve assembly forming with the working barrel assembly a suction and high pressure discharge chamber and being attachable to a conduit through which flow is to be set up and having a dual valve cage opening to said chamber, and means for connecting the barrel assembly to the valve assembly for concurrent rotation and a supply conduit of less volume 30 capacity than said chamber and whereby a suction tendency is set up as the opening motion of the barrel tends to set up a vacuum by drawing its supply from said conduit.

35. 9. A starter as set forth in claim 8, and in which said valve assembly includes a set of spring closed valves, said assemblies being relatively rotative, and means providing for concurrently opening the valves and including a ram carried by the barrel to engage one valve and move it 40 from its seat, and a device engaged by the moved valve to depress the other valve from its seat.

45. 10. A circulation starter including a set of spaced, spring-closed valves, a standing support therefor, a barrel working on said support and forming a suction chamber below the valves in communication with the space between the valves, a ram connected with the barrel to move against one of said valves, and push means between the valves; whereby when said ram acts 50 on the adjacent valve it will effect the opening of the other valve at the same time to establish a fluid by-pass.

55. 11. A starter as set forth in claim 10, and including means prohibiting such ram action except at a given angular position of the barrel as to the valve support.

60. 12. A circulation starter including a valve column having a tubular core fixed on its upper end, a barrel section slidably fitted about said core and having a tubular ram slidably fitting in said core and the barrel having a shoe slidably fitted on said column and forming a fluid chamber below said core, and valve means for controlling fluid flow from the said ram to the said 65 chamber; the upper end of said shoe presenting a larger effective area to pressure in said chamber than the cross area of the inner end of the said ram in the core.

70. 13. A circulation starter including a valve as- 75

sembly and a relatively movable barrel assembly, the valve assembly including a standing head core and a valve cage attached thereto, a tubular pillar supporting the cage, and the barrel assembly including a barrel having a shoe sliding on the pillar and forming a suction chamber below the cage, and said barrel sliding on the

core and having a part telescoping therein and presenting a cross area of less size than the end area of the said shoe in said chamber; whereby unbalanced fluid pressure on the shoe is available to actuate the barrel in one direction.
